UNITED STATES PATENT OFFICE.

HARVEY R. WOLFE, OF LOUISVILLE, KENTUCKY, ASSIGNOR TO A. G. MUNN, TRUSTEE, OF SAME PLACE.

CAR-BRAKE.

SPECIFICATION forming part of Letters Patent No. 357,257, dated February 8, 1887.

Application filed October 2, 1886. Serial No. 215,139. (No model.)

To all whom it may concern:

Be it known that I, HARVEY R. WOLFE, a citizen of the United States, residing at Louisville, in the county of Jefferson and State of Kentucky, have invented certain new and useful Improvements in Car-Brakes, of which the following is a full, clear, and exact description, reference being had to the accompanying drawings, forming part of this specification.

10 My invention has for its object, primarily, the production of a system of brakes for freight-trains under the control of the engineer, and whereby all of the brakes may be applied simultaneously at the will of the engineer.

15 The novelty of my invention will be herein set forth, and specifically pointed out in the claims.

In the accompanying drawings, Figures 1 20 and 2, Sheet 1, are side elevations of so much of a freight-train as is necessary to show the application of my invention, and with the axles in section, the near wheels being removed. Fig. 3, Sheet 1, is an enlarged rear elevation 25 of the tender. Fig. 4, Sheet 2, is a side elevation of a tender and box-car, representing a modification, with the axles in section and the near wheels removed. Fig. 5, Sheet 2, is a plan view of a box-car and its appliances.

30 Fig. 6, Sheet 2, is an enlarged plan view of the tender shown in Fig. 1. Fig. 7, Sheet 3, is a bottom plan view showing the application of the mechanism to the under side of a flat-car.

The same letters of reference are used to indicate identical parts in all the figures.

The rear axle of the locomotive-tender A has keyed or otherwise secured upon it a sprocket-wheel, B, from which a drive-chain extends around a second sprocket-wheel, C, 40 keyed or otherwise secured to a vertically-adjustable horizontal shaft, D, whose ends are journaled in boxes E, fitted into vertical slots in a frame, F, at each side of the tender-platform. Just within the frames F friction-pulleys G are keyed upon the shaft D, and these pulleys I preferably construct with paper or leather peripheries.

Journaled in suitable frames, H, upon the tender-platform is a shaft, I, which I call the 50 "winding-spool," which shaft has keyed upon

it friction-pulleys J, directly over the pulleys G. Above the shaft I is a third shaft, K, likewise provided with friction-pulleys L, in constant engagement with the pulleys J.

Small oscillating engines, M, of any approved 55 construction have their piston-rods secured by cranks or wrist-pins to the ends of the shaft K or disks thereon, so as to cause the revolution of said shaft when steam is admitted to the cylinders of the engines M. These cylinders are set quartering to prevent dead-centers.

To the lower sides of the frames F are secured other steam-cylinders, N, whose rods are connected to the sliding boxes E in such manner that when steam is admitted to the cylinders N the shaft D is raised to bring the pulleys G into contact with the pulleys J upon the winding-spool.

O is a steam-pipe extending under the 70 tender from the boiler, with branches P leading to the cylinders N, and A² is a second steam-pipe, with branches Q leading to the cylinders of the engines M. Any suitable valve, R, operated by levers S within reach of the 75 engineer admits steam to the cylinders M N or cuts it off. In this way either or both the power of the engines M and the traction of the tender may be employed to drive the spool I.

The cylinders N are preferably provided 80 with safety-valves T, of the usual or any suitable construction, for a purpose to be herein-after explained.

A wire cable or chain, U, is coiled upon the spool I, to which it is securely fastened, and 85 extends therefrom up over a guide-pulley, V, upon the top of the car just behind the tender, thence back and is fastened to and coiled upon a spool, W, loosely journaled upon a shaft, a, secured transversely across the top of the car 90 near its middle. This same shaft a has journaled upon it a similar spool, Y. To lock the spools W and Y to the shaft a, I employ clutch-blocks b, of the usual or any suitable construction, which, revolving with the shaft a, are 95 free to slide thereon into or out of engagement with the spools W and Y, and are operated by levers c, pivoted, as at d, to the top of the car and having forked ends with pins entering circumferential slots in the clutch-blocks. 100

The cable U, secured to and coiled upon the spool Y, extends rearward over a guide-pulley, Z, thence down under a snatch-block, e, which is secured to the upper end of a chain, 5 f, that extends down under a guide-pulley, g, and is connected to the brake-lever of the ordinary brakes now in use on freight-cars. From the snatch-block e the cable extends across under the snatch-block h of the next 10 car, and thence up and back in a similar manner to the rear of the train, where it is fastened in any suitable manner.

To hold the chains f substantially vertical and keep the snatch-blocks in their proper 15 place, guide-pulleys j are employed, which are journaled in brackets k, secured to the ends of the cars, as shown.

The inner ends of the spools W Y are provided with hand-wheels i, for readily revolving 20 said spools to take up the slack in the cable at any time, as in making up the train, and this is done by throwing the clutch-box of the spool out of gear, whereupon the spool is free to revolve independently either to pay out or take 25 up the cable. The cable is preferably made up in sections united by snap-hooks l for the more ready coupling and uncoupling of the same when making up the train or uncoupling the cars.

30 Where flat-cars are to be equipped the mechanism is applied to the underside thereof, as shown in Figs. 2 and 7, and where cars not equipped with my invention are taken into a train otherwise equipped with it, the cable 35 is passed over them and connected to the next equipped car.

It will be seen from this construction that when the engineer wishes to apply the brakes he merely has to admit steam to the cylinders 40 M or N, or both of them, whereupon the pulleys J start to revolve and communicate their motion to the winding-spool I, and the pulleys G, which constantly revolve, are thrown into contact with the pulleys J, and the cable U is 45 drawn taut and wound upon the spool I, thereby drawing uniformly upon all of the chains f and setting the brakes. The cutting off of steam at once releases the brakes, as will be readily understood.

50 In some cases the engines M and pulleys J may be dispensed with, in which case the weight of the tender alone would be relied upon to set the brakes. Again, as a modification of the means for revolving the spool I, the means shown in Fig. 4 may be employed, where a shaft, A', journaled in a swinging frame, B', and having keyed upon it a friction-pulley, C', is adapted to engage with a friction-pulley, D', keyed to the rear axle of the tender. 55 A sprocket-wheel keyed upon the shaft A' is connected by a chain to a sprocket-wheel, E', upon the spool I. To vibrate this frame so as to bring the pulleys C' D' into working

65 contact, a piston, F', is secured under the tender, whose rod is suitably connected to swinging frame B' in such manner that when steam is admitted to said cylinder said pulleys will be brought into working contact and the spool will be revolved. The cutting off of steam permits the frame B' to swing back and 70 carry the pulley C' away from the pulley D'. 75

While I have described and prefer the employment of steam for throwing the driving-pulleys into gear, it is evident that this could be done by the employment of levers to be 75 operated by hand.

Having thus fully described my invention, I claim—

1. In a system of car-brakes, a continuous cable connected to the brake-rods, having its 80 forward end secured to a winding-spool upon the locomotive-tender, steam-cylinders connected with said spool, steam-connection between said cylinders and the locomotive-boiler, and suitable mechanism within control of the 85 engineer for governing the flow of steam from the boiler to said cylinders, substantially as described.

2. In a system of car-brakes employing a continuous cable for the operation of the 90 brakes, the winding-spools W Y, provided with clutch-blocks for locking the same to their shaft, and means for the ready revolution of said spools, substantially as described.

3. In a system of car-brakes employing a 95 continuous cable for the operation of the brakes, the combination, with the rear axle of the tender, provided with a sprocket-wheel, of the shaft D, connected thereto and operated by the cylinders N and provided with friction-pulleys G, and the winding-spool I, provided 100 with friction-pulleys J, substantially as and for the purpose specified.

4. In a system of car-brakes employing a 105 continuous cable for the operation of the brakes, the combination, with the winding-spool I, provided with friction-pulleys J, of the oscillating engines M, shaft K, and friction-pulleys L, the parts constructed and arranged substantially in the manner and for the 110 purpose specified.

5. In a system of car-brakes employing a continuous cable for the operation of the 115 brakes, the combination, with the rear axle of the tender, provided with a sprocket-wheel, of the shaft D, connected thereto and operated by the cylinders N and provided with friction-pulleys G, the winding-spool I, provided 120 with friction-pulleys J, the oscillating engines M, and pulleys L, the parts constructed and arranged substantially in the manner and for the purpose specified.

HARVEY R. WOLFE.
